Primary Examiner — Elizabeth Albert(74) *Attorney, Agent, or Firm* — Christensen O'Connor Johnson Kindness PLLC(57) **CLAIM**

The ornamental design for a pen, as shown and described.

DESCRIPTION

FIG. 1 is an upper front left perspective view of a pen showing my new design;

FIG. 2 is a right side elevation view thereof, with the left side elevation view being a mirror image of the right side elevation view;

FIG. 3 is a rear elevation view thereof, with the front elevation view being a mirror image of the rear elevation view;

FIG. 4 is an enlarged top plan view thereof; and,

FIG. 5 is an enlarged bottom plan view thereof.

The broken lines shown in FIGS. 1 and 4 illustrate environmental subject matter and form no part of the claimed design.
